UNITED STATES PATENT OFFICE

ERNEST S. OSTLER, OF CHICAGO, ILLINOIS, ASSIGNEE, BY MESNE ASSIGNMENTS, TO
STROMBERG ELECTRIC COMPANY, A CORPORATION OF DELAWARE

RIBBON FEED MECHANISM

Application filed January 26, 1928. Serial No. 229,624.

My invention relates to improvements in ribbon feed mechanisms for time stamps and the like in which an inked ribbon is caused to travel across or cooperate with the face of the type or other impression means, the ribbon being arranged to be wound from one spool or reel onto another.

One of the objects of my invention is to provide improved means for reversing the direction of travel of the ribbon in which the time of such reversal is controlled by that one of the ribbon rolls which is diminishing in diameter.

A further object of my invention is to provide improved means for reversing the direction of the ribbon travel in which a multiplying lever is provided whereby relatively slight ribbon travel will cause a relatively great movement of the ribbon reversing mechanism.

A further object of my invention is to provide improved means for driving the ribbon rolls.

In the drawings in which an embodiment of my invention is shown,

Figure 1 is a side elevation of a time stamp provided with my improved ribbon feed mechanism, a portion of the casing being broken away to show the interior construction;

Fig. 2 is a top plan view of the ribbon feed mechanism, parts being broken away;

Fig. 3 is a side elevational view of the ribbon feed mechanism;

Fig. 4 is a side elevational view of the mechanism for controlling the direction of travel of the ribbon; and

Fig. 5 is a view similar to Fig. 4 but with the parts in a different position.

The construction shown is in the nature of an improvement on the construction shown in the patent to Crook, No. 941,130.

Referring to the drawings in detail, the construction shown therein comprises a time stamp having a base or platen 1 and a manually operable oscillatable stamp head 2 pivotally mounted on the base at 3. Any suitable time controlled type mechanism may be used, this not being shown in detail, as no claims are made to details of the time con-

trolled type mechanism. The reversible ribbon feed mechanism is mounted on the oscillatable stamp head 2 and comprises a pair of ribbon spools 4 and 5, an actuating slide member 6 which is operated each time the stamp head is manually depressed in the printing operation, and transmission between said actuating member and the two ribbon spools 4 and 5. This transmission comprises two trains mounted on a rockable frame 7, this frame when in one extreme position bringing one of said trains into operative relation with one of the ribbon spools, and when in the other extreme position bringing the other train into operative relation with the other ribbon spool. The actuator 6 has a pin and slot connection with the stamp head and has its upper end pivotally connected with a lever 8 pivotally secured at 9 to the stamp head. A coil tension spring 10 is provided which normally holds this actuator in the position shown in Figs. 1 and 3. When the stamp head is depressed the foot 11 of the actuator engages a lug 12 on the platen 1 and moves the actuator upwardly relatively to the stamp head. When the stamp head is released and returns to the position shown in Fig. 1, the coil spring 10 returns the actuator to the position shown in Fig. 1 so that each stamping movement of the stamp head causes a complete oscillation of the lever 8. This lever has pivotally mounted thereon an actuating pawl 13 which cooperates with a ratchet wheel 14 mounted on a shaft 15 secured to the stamp head 2 so that each oscillation of the lever causes the ratchet wheel to be advanced. A spring pressed pawl 16 is provided to prevent retrograde movement of the ratchet wheel.

The transmission from this ratchet wheel to the right hand ribbon spool, as seen in Figs. 1, 2, and 3, comprises a pinion 17 rotatable with the ratchet wheel 14, a second pinion 18 meshing with the first pinion and mounted on the rockable frame 7, a third pinion 19 meshing with said second pinion and also mounted on this rockable frame 7, a fourth pinion 20, mounted on the stamp head with respect to which the said third pinion is movable into 100

and out of engagement, a fifth pinion 21 also mounted on the stamp head and rotatable with the fourth pinion 20, a sixth pinion 22 mounted on the stamp head and meshing 5 with the pinion 21, and a gear 23 meshing with the sixth pinion and rotatable with the right hand ribbon spool 4.

The transmission from the ratchet wheel 14 to the left-hand ribbon spool comprises the 10 first pinion 17 heretofore referred to, a gear 24 meshing with this first pinion 17 and mounted on the rockable frame 7, a pinion 25 with respect to which said gear is movable into and out of engagement, a pinion 26 also 15 mounted on the stamp head and rotatable with the pinion 25, a pinion 27 mounted on the stamp head and meshing with the pinion 26, and a gear 28 meshing with said pinion 27 and rotatable with the left-hand ribbon 20 spool 5. It will be seen that when the rotatable frame is in the position shown in Figs. 2, 3, and 5, that the gear 24 will be in mesh with the pinion 25 and that stamping movement of the stamp head will cause the left-hand ribbon spool to be driven to wind up the ribbon thereon and that when the rockable frame is in the position shown in Fig. 4, the pinion 19 will be in mesh with the pinion 20 and that each stamping movement of the 30 stamp head will cause a movement of the right-hand ribbon spool 4 to wind up the ribbon thereon.

The ribbon controlled means for controlling the position of the rockable frame 35 (and thus controlling the direction of the travel of the ribbon) will now be described. The rockable frame 7 is provided with a rock plate 29 with which cooperate a pair of pivoted ribbon controlled dogs 30 and 31, one 40 of which moves said rockable member 7 to one extreme position and holds it there for a time, and then releases it, and the other of which moves said rockable member to its other extreme position and holds it there for 45 a time, and then releases it, a pair of intermediate lost motion rock members 32 and 33 pivotally mounted about the same axes 34 and 35 respectively as the pivoted dogs, and a pair of levers 36 and 37, fulcrumed about 50 the axes 34 and 35, and controlled by the ribbon rolls 38 and 39 respectively for actuating the rock members respectively. It will be noted that these ribbon controlled levers overlap each other, and that each lever controls that dog which is on the opposite side of the axis 15 of the rockable member from that on which the lever itself is pivoted. This enables the arms 40 of the levers which engage the intermediate rock members to be 55 made considerably longer than the arms which are controlled by the rolls of ribbon, so that a comparatively slight change in the diameter of the ribbon roll will give a considerable degree of movement to the rock members. The short arms 41 of the levers

bear on the shoes 42 and 43 respectively which engage the ribbon rolls, these shoes extending substantially across the entire face of the ribbon so that the pressure is widely distributed and not excessive at any point. The engagement between the lever and rock member is effected by means of a laterally extending finger 44 on the lever which engages a cooperating laterally extending finger 45 on the intermediate rock member. It will also be noted that, because of the fact that each lever arm 40 engages the rock member which is on the opposite side of the axis of the rockable frame 7, the releasing operation which permits the tilting and reversing action of this rockable frame is effected by that one of the rolls on the spools which is diminishing in diameter. The advantage of this is that a relatively small travel of the ribbon will cause a greater change in diameter of the diminishing roll than the same amount of ribbon travel would cause in the diameter of the roll which is increasing in diameter. This makes the point of reversal of the ribbon travel much more definite than in the construction shown in the Crook patent referred to in which the reversal is controlled by the ribbon roll which is increasing in diameter. With the construction of the Crook patent the point of reversal of the ribbon might vary as much as several inches while with my improved control the point of reversal of the ribbon does not vary more than a fraction of an inch.

The holding operation of each dog is effected by the engagement of the arcuate edge 46 of the dog with the edge 47 of the rock plate. The actuating function of the pivoted dog is effected by the engagement of the point of the dog with the upper surface of the rock plate. Thus in Fig. 4 the right-hand dog 30 is holding the rock plate 29 against the action of the left-hand dog 31 which is tending to tilt the rock plate to the position shown in Fig. 5 because of the action of the coil tension spring 48 which connects the intermediate rock members 32 and 33. In Fig. 5 the left-hand dog 31 has its arcuate holding edge 46 in engagement with the edge 47 of the rock plate and thus holds the rock plate against its tendency to rock back to the position shown in Fig. 4 under the action of the point of the right-hand dog which is pressing down on the upper surface of the rock plate.

The lost motion connection between each intermediate rock member and its dog is effected by means of a pin 49 mounted on the rock member and operating in a slot 50 in the pivoted dog. The purpose of this lost motion connection is to permit a slight additional rocking movement of the dog after it has released the rock plate, this additional rocking movement being made without any corresponding movement of the rock member, the only resistance which is offered to

this additional movement being the slight resistance offered by the light coil tension spring 51 which connects the dog with the rock member. The longer arms 40 of the two levers are urged upwardly by means of a pair of springs 52 connected to these levers at 53, said springs being connected at their upper ends to an equalizing lever 54 rockably mounted on a fulcrum pin 55 secured to the stamp head 2.

I will now describe how the parts are shifted from the position shown in Fig. 4 to the position shown in Fig. 5, which shift would cause a reversal in the direction of ribbon travel. In Fig. 4 the rockable member 7 is in a position which will cause the ribbon to be wound up on the right-hand ribbon spool and unwound from the left-hand ribbon spool. The right-hand roll 38 is thus increasing in size and the left-hand roll 39 diminishing in diameter; thus the action of the ribbon on the rolls will be such as to cause the right-hand lever arm 40 to move downwardly from the position shown in Fig. 4 to the position shown in Fig. 5 against the action of the right-hand coil tension spring 52, and such as to permit the left-hand lever arm 40 to move upwardly under the action of the left-hand coil tension spring from a position shown in Fig. 4 to the position shown in Fig. 5. As the left-hand lever arm 40 moves upwardly as aforesaid, its laterally extending finger 44 will engage the laterally extending finger 45 of the intermediate rock member 32 and as soon as the lost motion has been taken up between this intermediate rock member 32 and the pivoted dog 30, the pivoted dog will also be moved upwardly along with the intermediate rock member until the dog is moved up so far that its lower point 56 passes the upper surface of the rock plate 29 and thus releases this rock plate so that it can be rocked by the action of the lower point 56 of the left hand dog which is pressing down on the rock plate because of the action of the coil tension spring 48. Meantime, the right-hand lever arm 40 will have been moved downwardly so that its laterally extending finger 44 will be so far down that it will be entirely out of the path of travel of the laterally extending finger 45 on the left-hand intermediate rock member 33. This left-hand intermediate rock member is therefore free to move from the position shown in Fig. 4 to the position shown in Fig. 5 during which movement it rocks the rock plate 29 from the position shown in Fig. 4 to the position shown in Fig. 5, and furthermore moves to a position in which its arcuate holding edge 46 engages the edge 47 of the rock plate, thus holding the rock plate in the position shown in Fig. 5.

It will be seen that the final releasing movement of the right-hand dog 30 is controlled by the left-hand ribbon roll 39 which at the moment of release is relatively small in di-

ameter so that a slight ribbon travel would quickly change the diameter of this relatively small ribbon roll. As previously indicated this control of the time of reversal by means of the small ribbon roll has a decided advantage in that it makes the point of cut-off less subject to variation than in the type of reverse in which the reverse is controlled by the larger of the two ribbon rolls.

The movement of the parts from the position shown in Fig. 5 back to that shown in Fig. 4 is substantially a reversal of the movement described above. In Fig. 5 the parts have been moved to a position which will cause the ribbon to be wound up on the left-hand spool from the right-hand spool. The left-hand ribbon roll 39 is thus increasing in size and the right-hand ribbon roll 38 is diminishing in size. The left-hand lever arm 40 will therefore be forced downwardly from the position shown in Fig. 5 to the position shown in Fig. 4 against the action of the left-hand coil tension spring 52 and the right-hand lever arm 40 will be permitted to be moved upwardly under the action of the right-hand coil tension spring 52 from the position shown in Fig. 5 to the position shown in Fig. 4. Thus in the upward movement of the right-hand lever arm its laterally extending finger 44 will come into engagement with the laterally extending finger 45 on the intermediate rock member 33, and as soon as the lost motion between this rock member 33 and the pivoted dog 31 has been taken up, the pivoted dog also will be moved upwardly along with the intermediate rock member and will finally be moved to a position in which its lower point 56 will move past the upper edge of the rock plate 29 and release this rock plate for rocking movement. During this movement the left-hand lever arm will have been moved downwardly against the action of the coil tension spring 52 until its laterally extending finger 44 has been moved downwardly so far that it will be completely out of the path of travel of the laterally extending finger 45 on the intermediate rock member 32. Therefore, as soon as the left-hand rocking dog 31 has released the rock plate 29, the right-hand dog 30 will rock the rock plate from the position shown in Fig. 5 to the position shown in Fig. 4 and in its movement the lower point 56 of the actuating dog will finally move the rock plate to a position in which the lower point of the dog can slip past the edge 47 of the rock plate and move to the holding position shown in Fig. 4.

The right-hand lever 36, intermediate rock member 32, and pivoted dog 30 are all mounted on the same pivot pin 34, and also the left-hand lever 37, intermediate rock member 33, and dog 31 are mounted on the same pivot pin 35. The tension of the coil spring 48 connecting the two intermediate members is ample to overcome the resistance of the com-

paratively light, closely coupled springs 51 which connect the pivoted dogs with the intermediate members respectively so that the rocking movement of the rock plate is effected 5 the instant the rock plate is released by the pivoted dog.

The operation has been described in connection with the construction of the parts. To recapitulate briefly, every time the operator 10 brings the stamp head down to effect an impression, the foot 11 of the slide member engages a lug 12 on the platen and effects a rocking movement of the pawl carrying lever 8 which causes a stepped movement of the ratchet wheel 14. This stepped movement of the ratchet wheel is transmitted to one or the other of the ribbon spools (depending on whether the rock plate 29 is in the position shown in Fig. 4 or the position shown in 15 Fig. 5), and this causes the ribbon to be gradually wound up on one spool and unwound from the other. At a certain stage in the unwinding operation one of the ribbon rolls becomes so small that the holding dog is moved 20 to releasing position whereupon the rocking plate 29 snaps immediately to its other extreme position, thus shifting the drive to the other spool.

While I have described but one embodiment 30 of my invention, it is obvious that many modifications therein may occur to those skilled in the art, and I desire, therefore, that my invention be limited only by the scope of the appended claims and by the prior art.

35 I claim:

1. The combination with a pair of ribbon spools and a member rockable back and forth for shifting the drive for the spools of a reversible ribbon feed, a gear coaxial with said 40 rockable member and gearing mounted on said rockable member for alternatively driving one or the other of said spools, of means for controlling the time of said shift, controlled by that one of the ribbon rolls which is diminishing in diameter.

2. The combination with a member rockable back and forth for shifting the drive for the spools of a reversible ribbon feed, of means for controlling the time of said shift, controlled by that one of the ribbon rolls which is diminishing in diameter, said means comprising a pair of oscillatable members 50 pivotally mounted on opposite sides of the axes of said rockable member, one of which oscillatable members moves said rockable member to one extreme position and holds it there for a time and thereafter releases it, and the other of which moves said rockable member to its other extreme position and holds it there for a time, a pair of actuating members for 55 said holding members respectively, having a lost motion connection therewith, said actuating members being spring-pressed in one direction, each actuating member serving to move its corresponding holding member from a position in which it holds said rockable member against rocking movement to a position 60

ing pivoted on the opposite side of the axis of the rockable member from that on which the oscillatable member which it moves is pivoted.

3. The combination with a member rockable back and forth for shifting the drive for the spools of a reversible ribbon feed, of means for controlling the time of said shift, controlled by that one of the ribbon rolls which is diminishing in diameter, said means comprising a pair of oscillatable members pivotally mounted on opposite sides of the axes of said rockable member, one of which oscillatable members moves said rockable member to one extreme position and holds it there for a time and thereafter releases it, and the other of which moves said rockable member to its other extreme position and holds it there for a time and thereafter releases it, and a pair of rock members pivotally mounted on opposite sides of the axis of said rockable member for moving said oscillatable members respectively from holding to releasing position, each rocking member being pivoted on the opposite side of the axis of the 70 rockable member from that on which the oscillatable member which it moves is pivoted, each rocking member being a lever of the first class, the shorter arm of the lever engaging the ribbon roll and the longer arm actuating the oscillatable member whereby a relatively slight ribbon travel will cause a relatively great movement of the oscillatable member. 75

4. A reversible ribbon feed mechanism comprising a driving gear, two rotatable spools 100 for the ribbon, two gears alternately driven in opposite directions for controlling the rotation of the spools respectively, a rockable member, two alternate transmissions mounted on said rockable member, said rockable member when in one extreme position bringing one of said transmissions into operative relation to provide transmission between said driving gear and one of said driven gears, to cause it to drive one of said spools to wind up the 105 ribbon thereon from the other spool and said rockable member when in the other extreme position, bringing the other of said transmissions into operative relation to provide transmission between said driving gear and the other of said driven gears to cause it to drive the other of said spools to wind up the ribbon thereon, a pair of members, one of which moves said rockable member to one extreme 110 position and holds it there for a time, and the other of which moves said rockable member to its other extreme position and holds it there for a time, a pair of actuating members for 115 said holding members respectively, having a lost motion connection therewith, said actuating members being spring-pressed in one direction, each actuating member serving to move its corresponding holding member from a position in which it holds said rockable member against rocking movement to a position 120

125 130

tion in which it releases said rockable member to permit the other spring-pressed holding member to rock the rockable member; after this rocking movement the holding member which has just released the rockable member being in a position tending to rock the rockable member, the other holding member after having rocked the rockable member being in a position to hold the rockable member in the position to which it has been moved, and means whereby that one of the holding members which is holding the rockable member is moved to releasing position, controlled by that one of the rolls on the spools which is diminishing in diameter, said means comprising two releasing members, one for each actuating member, the position of which releasing members is controlled by the rolls of ribbon on the spools.

20 5. The combination with a member rockable back and forth for shifting the drive for the spools of a reversible ribbon feed, of means for controlling the time of said shift, controlled by that one of the ribbon rolls 25 which is diminishing in diameter, said means comprising a pair of control members movable back and forth and mounted on opposite sides of the axis of said rockable member, one of which control members moves said rockable member to one extreme position and holds it there for a time and thereafter releases it, and the other of which moves said rockable member to its other extreme position and holds it there for a time and thereafter releases it, and a pair of rock members pivotally mounted on opposite sides of the axis of said rockable member for moving said control members respectively from holding to releasing position, each rock member being pivoted on the opposite side of the axis of the rockable member from that on which the control member which it moves is mounted.

35 In witness whereof, I have hereunto subscribed my name.

40 45 ERNEST S. OSTLER.
